COLLAR SUPPORT

Alexander S. Steinman, Chicago, Ill., assignor of
one-half to Nathan Steinman, Chicago, Ill.

Application July 3, 1947, Serial No. 758,766

3 Claims. (Cl. 223—83)

1

The invention relates to improvements in collar supports of a kind used by laundries to reinforce the collar of collar-attached shirts.

An object of the invention is to provide an inexpensive and efficient support for reinforcing the collar of a collar-attached shirt by means insertable between the inner and outer folds thereof, and which includes novel integral means to prevent its displacement.

Another object of the invention is to provide a collar support with means stamped from the body thereof and adjacent to one of its edges adapted to interlock with the buttonhole strip of a shirt.

Another object is to provide a collar support of a kind that is easily and quickly positioned inside the neckband of a collar attached shirt and detachably engaged with the shirt and neckband to prevent displacement of the support.

Other and further objects of the present invention will be apparent from the following description and claims and are illustrated in the accompanying drawing. Other embodiments of the invention embodying the same principle may be used, and structural changes may be made as desired by those skilled in the art, without departing from the present invention and the purview of the appended claims.

In the drawing:

Fig. 1 is a fragmentary perspective view of a collar-attached shirt showing the improved collar support in place therein.

Fig. 2 is a plan view of the collar support.

Fig. 3 is a sectional detail view taken substantially on line 3—3 of Fig. 1.

Fig. 4 is a fragmentary perspective view of a collar-attached shirt showing the support positioned within the neckband.

Fig. 5 is a sectional detail view taken on line 5—5 of Fig. 4.

Referring to the disclosure in Figs. 1 to 3 inclusive, in the accompanying drawing, the collar support 10 is constructed from a suitable piece of flexible material such as, for example, medium weight cardboard, which is stamped from a blank sheet to provide a longitudinally curved strip of substantially uniform width. The strip has upper and lower curved longitudinal edges 11 and 12, and its end edges are suitably serrated or otherwise provided with protuberances 13 throughout substantially the entire length of said edges and include, at the junctures of said edges with the lower edge 12, nibs 14, all provided for purposes to be described presently.

The strip of flexible material may be inserted

2

between the inner fold or neckband 15 and the outer fold 16 of a collar on a collar-attached shirt 17. When inserted in place, as illustrated in Fig. 1, the collar support conforms substantially to the curvature of the collar and the serrated end edges and nibs 14 engage frictionally with the inner faces of the outer fold 16 of the collar to assist in retaining the collar support against displacement.

Positive means is provided in the collar support 10 to prevent inadvertent displacement or shifting of the support when it is in the position shown in Fig. 1. To this end, a tongue 18 is struck out from the body of the strip substantially midway between the ends 13 and adjacent to the lower curved longitudinal edge 12. This tongue 18 is best formed by die-cutting or otherwise severing it from the body of the strip along the line 19, which when viewed as shown in Fig. 2, is of irregular contour and terminates at one end, as at 20, onto the edge 12 of the strip and at its other end 21 at substantially the transverse medial portion of said strip. The irregular contour of the slit 19, adjacent to the end 20, defines a barb or hook-like projection 22 on the free end of the tongue 18.

When the collar support is inserted in the position of use, the tongue 18 is inserted beneath the buttonhole strip 23 of the shirt and the barb-like projection 21 engages over the free edge of the button strip 25 to prevent easy withdrawal of said tongue due to any tendency of the collar support to shift circumferentially. It should be quite evident also that by locating the button strip engaging tongue 18 on the lower edge 12 of the collar support, said tongue has its bottom edge rested snugly against the fold 24 in the shirt at the juncture of the button strip 25 with the inner fold 15 of the collar. This disposition of the tongue 18 with relation to the fold 24 materially increases the frictional resistance offered to displacement of the collar support downwardly out of and away from its fully telescoped position between the inner and outer collar folds 15 and 16. The structure also is such as to greatly facilitate the insertion of a collar support between the collar folds, it being a simple procedure to initially thrust the collar support upwardly between the collar folds and then shift it circumferentially in a direction to engage the tongue 18 beneath the button hole strip 23. The structure further is very practical because its use and the function of its parts are not dependent upon the presence of or location of any

buttons, buttonholes or other elements frequently present in a shirt of the character disclosed.

Referring specifically to the mode of application of the collar support as illustrated in Figs. 4 and 5, it will be noted that the collar support 10 is inserted on the inside of the neckband 15. This affords a very simple method of application whereby the collar support is easily and quickly thrust into position, with the tongue 18 extending forwardly between the lower button hem 25 and the back 26 of the shirt. The nibs 14 likewise engage between the shirt back 26 and the bottom edge of the neckband 15, while the serrated edge 13 frictionally engages the inside face of the neckband to resist displacement. In some instances of application the barb-like end 22 of the tongue 18 will engage over the margin of the button hem 25 to further resist separation of the collar support from the shirt.

Although a single embodiment of the invention has been shown in detail in the accompanying drawing, and fully described in the foregoing description, it should be understood that the invention may be installed in a plurality of positions and is capable of embodying a variety of modifications in detail without departing from the spirit of the invention or the scope of the appended claims.

I claim:

1. Collar bracing and stiffening means for collar-attached shirts, comprising an elongated strip of flexible material for insertion inside the neckband of a collar, frictional means on the ends of said strip engageable with the inside surface of the neckband, a tongue on the lower longitudinal edge of said strip midway between its ends engageable beneath the shirt front adjacent the neckband, a barb on the free end of the tongue

engageable over the edge of the button strip adjacent the neckband and means on the free ends of said strip engageable beneath said neckband.

- 5 2. Collar bracing and stiffening means for collar-attached shirts, comprising an elongated strip of flexible material for insertion between the inner and outer folds of the collar, the material of said strip being cut adjacent its lower edge, which cut 10 merges with the lower edge to form a tongue insertable beneath the button-hole strip of the shirt, and a hook-like projection on the free end of the tongue engageable with an edge of the button strip of said shirt to resist withdrawal.
- 15 3. Collar bracing and stiffening means for collar-attached shirts, comprising a collar supporting member for insertion between the inner and outer folds of the collar, and a tongue extending longitudinally of said member along one of its 20 edges and being insertable beneath the button-hole strip of the shirt adjacent the neckband, said tongue having a hook-like projection on its free end and being of such length as to bridge the button strip and engage the projection over 25 the button strip edge.
